TRAFFIC SIGNALING MEANS FOR VEHICLES

Original Filed Sept. 29, 1922 2 Sheets-Sheet 2

Inventor:
Frederick W. Hottenroth,
By his Attorney, Leo. W. Niarch

UNITED STATES PATENT OFFICE.

FREDERICK W. HOTTENROTH, OF PARK HILL, NEW YORK.

TRAFFIC-SIGNALING MEANS FOR VEHICLES.

Application filed September 29, 1922, Serial No. 591,245. Renewed February 6, 1924.

To all whom it may concern:

Be it known that I, FREDERICK W. HOTTENROTH, a citizen of the United States, and a resident of Park Hill, county of West Chester, and State of New York, have invented certain new and useful Improvements in Traffic-Signaling Means for Vehicles, of which the following is a specification.

10 While adaptable for various purposes and uses where a plurality of signals are to be actuated separately and independently, my present improvements relate more particularly to the type of signaling means set forth in Letters Patent No. 1,403,082, issued to me January 10th 1922, and are designed to afford apparatus of this character, not only for use on automobiles, motor boats, trolley cars, or other motor driven vehicles 18 generally, in accordance with the various exigencies of travel or road traffic, but also for installation in localities and positions where traffic and analogous signals are desirable.

To this end the invention consists primarily and essentially in the combination, with a plurality of rockable indicators, of means for actuating and controlling the same individually and independently through the medium of a single rotatable reciprocative shaft, manually manipulatable, substantially in the manner and for the purposes hereinafter fully set forth.

In the accompanying drawings I exemplify a practical embodiment of the essential features of my present invention, although I do not limit myself to the identical form and construction of parts shown, since various modifications may be resorted to in minor details with like result, and without departing from the spirit and intent of said invention.

With this understanding,

Fig. 1, represents a front elevation of my improved signaling apparatus, the front of the indicator, container, or shield compartment being omitted to more clearly show the operative parts;

Fig. 2, is a section taken upon the planes of the zig-zag line 2—2, Fig. 1;

Fig. 3, is a top view of the indicators and connective parts, the top of the shield compartment being broken away in part, and in section;

Fig. 4, is a diagrammatic illustration of the operation of the "stop" indicator;

Fig. 5, is a diagrammatic illustration of

the operation of the indicator used to signal traffic deviation to the left;

Fig. 6, is a diagrammatic illustration of the actuation of the indicator used to signal traffic deviation to the right;

Fig. 7, is a detail view of one form of coupling between the reciprocatory rotative shaft sections;

Fig. 8, is a sectional detail of the connection between the outer end of the actuating shaft and its cross head with which the indicator link-levers are connected;

Fig. 9, is a cross section of the outer section of the actuating shaft taken upon plane 70 of line 9—9 Fig. 1, but upon a larger scale;

Fig. 10, is a sectional elevation taken upon plane of line 10—10 Fig. 1;

Fig. 11, shows the indicator link-levers in detail;

Fig. 12, is a detail view of the parts by which one of the indicators is actuated as viewed from the side thereof opposite to that shown in Fig. 1.

The rockable indicators R, L, and S, are pivotally and pendently supported on a fixed fulcrum arbor F, as shown more particularly in Fig. 2, of the drawings, spacing washers f, f, or the equivalent thereof being interposed between them, and the fulcrum arbor F, itself being supported on and between the front plate c, and the rear plate c', of a shield compartment or container C, which is fixedly mounted and located. This container, or shield compartment C, may be 90 of any desired shape, provided it affords ample concealment for the said rockable indicators R, L, and S, when retracted, and also for the links, etc., by which they are actuated. As shown in the drawings, said 95 shield C, is of circular configuration, and may afford support for a rear observation mirror M, such as usually employed on automobiles, etc. A tubular extension c² of the shield compartment C, constitutes a 100 bearing for the support of the indicator-control section A, of the actuating shaft, the latter, considered in a unitary sense, consisting of said section A, and a manipulative section A', mounted in a bearing bracket 105 B, rigidly affixed to the dash board of an automobile, or other suitable support positioned conveniently for manipulative purposes—i. e., for the control and operation of the actuating shaft, A, A', the opposed ends 110 of which are coupled together, either by an articulative joint a, as in Fig. 7, or by a

section of flexible shafting a' , as indicated symbolically in Fig. 1, of the drawings, the object of this articulative or flexible end to end shaft coupling being to compensate for any possible lack of accurate alignment between the two shaft sections A, A', as installed for use.

The bearing bracket B, is formed with a longitudinal slot b , the ends of which form stop shoulders b , b^2 , which limit the extent of movement of the handle a^2 , the shank of which extends through said slot b , and is rigidly secured to the manipulative shaft section A, as shown more particularly in Fig. 10 of the drawings.

Said longitudinal slot b , in the bearing bracket B, is formed with a lateral off set or recess b^x , (see particularly Figs. 1 and 10, of the drawings), which admits of the partial rotation of the actuating shaft A, A', on its longitudinal axis, when the shank of the handle a^2 , is in coincidence therewith, which is when the said shaft A, A', is in normal position, with all the indicators R, L and S, retracted and pendent within the containing shield C, as shown in the first three figures of the drawings.

To the "stop" indicator S, above the fulcrum arbor F, is pivotally attached a rocker arm s , which in turn is pivotally connected with a rock-lever s' , fulcrumed on a stud s^2 , rigidly mounted upon a wall of the container shield C, as will be seen by reference more particularly in Fig. 3, in conjunction with Fig. 1, of the drawings. Near the forward end of the indicator-control section A, of the actuating shaft is a laterally projecting trip arm a^3 , positioned to contact with the inner end of the rock-lever s' , when the actuating shaft A, A', is turned on its longitudinal axis. That is to say, when the shank of the handle a^2 , is turned down into the lateral recess b^x , the partial rotation of the actuating shaft A, A', on its longitudinal axis to the extent, approximately, of one-fourth of a rotation, raises the trip arm a^3 , into contact with the lever s' , rocking the latter on its fulcrum s^2 , and causing it to depress the rocker-arm s , and thereby raise the "stop" indicator S, to a position substantially at right angles to its normal pendent position,—these changes in relative positions of parts being indicated by dotted lines in Fig. 4, of the drawings. The indicator S, thus raised at right angles to its normal pendent position, protrudes beyond the container shield C, and signals the intent of the driver to stop the vehicle. When the shank of the handle a^2 , is raised out of the recess b^x , the trip arm a^3 is lowered, allowing the rock-lever s' , rocker-arm s , and indicator S, to return to their normal positions. It is to be noted that the above described operation of the "stop" indicator S, is effected by a partial turn only of the actuating shaft A,

A', on its longitudinal axis, and while said actuating shaft A, A', is otherwise stationary. When the shank of the handle a^2 , is out of the slot b^x , and in alignment with the longitudinal slot b , in the bearing bracket B, the actuating shaft A, A', is reciprocatable within the limits of the slot b , the notch or recess b^x , coinciding with the medial or neutral position in which the indicators R, and L, are pendent and in normal position.

The outer end of the indicator control section A, of the actuating shaft has pivotally mounted upon it a cross head a^4 , formed with bracket arms a^5 , a^6 , which carry screw studs a^7 , a^8 , for engagement with longitudinal slots in the link-levers l , and r , which are pivotally connected respectively with the indicators L, and R, on opposite sides of the fulcrum arbor F. Thus the link-lever r , is pivotally connected to the indicator R, below said fulcrum arbor F, as shown in Figs. 1, and 5, while the link-lever l , is pivotally connected with the indicator L, above said fulcrum arbor F, as shown in Figs. 1, and 6, of the drawings, so that the indicator R, which bears a pointer r' , to designate intended traffic to the right of the vehicle, has to be pushed outward to rock it into visual signal position, whereas, the upper portion of the indicator L, which bears a pointer l' , indicative of intent to deviate to the left, has to be pulled inward in order to rock said indicator L, into visual position.

The cross head a^4 , is pivotally mounted on the end of the shaft section A, so as to admit of the partial rotation of the actuating shaft A, A', for the purpose of operating the "stop" signal S, as hereinbefore set forth. Fig. 8, shows a pivotal mount of this character, although I do not limit myself thereto.

As before stated, Fig. 1, shows the operative parts at rest in their normal positions, by reference to which figure more particularly, it will be seen that under these conditions the slot r^2 , in the link-lever r , extends mainly to the rear of the stud a^7 , whereas, the slot l^2 in the link-lever l , extends mainly in front of its engaging stud a^7 . Thus, when the actuating shaft A, A', is slid longitudinally to the left, by means of the handle a^2 , until the shank thereof rests against the end b^2 , of the bearing bracket slot b , the stud a^7 , will push the link-lever r , and indicator R, outward as illustrated by dotted lines in the diagram Fig. 5; and conversely, when the actuating shaft A, A', is slid longitudinally to the right by means of the handle a^2 , until the shank thereof rests against the opposite end b' , of the said slot b , the stud a^7 , will pull the link-lever l , and upper part of the indicator L, backward, thereby causing the main portion of the indicator L, to protrude visibly beyond the encasement shield S, as illustrated by dotted lines in Fig. 6. In both reciprocatory move-

ments of the actuating shaft A, A', the elongated slots r^2 and l^2 , in the link-levers r , and l , admit of, and compensate for, the extent of movement of cross head a^4 involved,—i. e. the slot l' , admits of the advance of the link-lever r , by the stud a^8 , without disturbance of the link-lever l , and its indicator L, and in like manner the slot r^2 admits of the retraction of the link-lever 10 l , and the advance of its indicator L, without disturbing the link-lever r , and its indicator R.

In order to yieldably hold the indicators R, L, and S, against looseness or play in either position, I form their upper edges, above the fulcrum F, with notches n , n , for engagement with a spring detent d , as indicated particularly in Figs. 1, 2, and 3 of the drawings.

20 It will be seen by the foregoing description that by my reciprocatory and rockable actuating shaft A, A', I control three indicators, individually and independently, by simple means of manipulation, a single 25 knob or handle answering the purpose.

I have herein shown and described my improved signaling means as applied and adapted to the exhibition of indicators on one side only of a vehicle, or other location 30 of installation, although it is obvious that my invention would include a like manipulation of a duplication of indicators at both ends of a reciprocatory and rockable actuating shaft, by a simple modification in the 35 relative arrangement of the elongated slots in the link-levers.

Furthermore, the essential features of my invention are applicable and adaptable to other uses and installations in which a plurality of signals, signs, or indicators are 40 to be singly and independently operated and displayed, as for instance for fixed traffic regulating stations, or for any analogous use.

I have herein shown and described my invention as adapted to the independent operation of three indicators. A single indicator, or any plural number of indicators, may, however, be mounted and manipulated, substantially as herein set forth, by a simple 45 duplication of the parts and appurtenances described and claimed herein. Thus, for instance, the trip arm a^3 , may be duplicated on the opposite side of the control section A, of the actuating shaft, together with the 50 rock lever s' , and rocker arm s , suitably mounted, and connected with an equivalent of the indicator S, bearing a suitable pointer or sign; and other reproductions or nullifications of operative parts may be resorted 55 to in adapting the essential features of my invention to specific requirements, as may be found expedient in practice.

What I claim as my invention and desire to secure by Letters Patent is,

1. In signaling means of the character 65 designated, the combination of a pivotally supported indicator, a rocker arm pivotally connected therewith, a rock-lever pivotally connected with said rocker arm and fulcrumed on a stationary part, a reciprocatory rotative actuating shaft formed with a trip arm for engagement with said fixed fulcrum rock-lever, another pivotally supported indicator, and a rock-lever pivotally connected directly therewith and with said 70 reciprocatory rotative actuating shaft, substantially in the manner and for the purpose described.

2. In signaling means of the character 75 designated, the combination of two pivotally supported indicators, two longitudinally slotted rock-levers each pivotally connecting one indicator independently with a common reciprocatory actuating shaft, 80 and said actuating shaft, the slots in the said rock-levers admitting of the independent movement of the respective rock-levers when the actuating shaft is moved in opposite directions, all of said indicators being independently actuated by said 85 common reciprocatory and rotative actuating shaft, substantially in the manner and for the purpose set forth.

3. In signaling means of the character 90 designated, the combination of a pivotally supported indicator, a rocker arm pivotally connected therewith, a rock-lever pivotally connected with said rocker arm and fulcrumed on a stationary part, a reciprocatory rotative actuating shaft formed with 95 a trip arm for engagement with said fixed fulcrum rock-lever, two other pivotally supported indicators and two longitudinally slotted rock-levers, each pivotally connecting one indicator independently with said 100 reciprocative actuating shaft, the slots in the two said slotted rock-levers admitting of their independent movement when the said actuating shaft is reciprocated, all of 105 said indicators being independently actuated by said common reciprocatory and rotative actuating shaft, substantially in the manner and for the purpose described.

4. In signaling means of the character 110 designated, the combination of a pivotally supported indicator, a rock lever pivotally connected therewith, and with a reciprocative actuating shaft, said shaft formed in two sections flexibly coupled together, means for operating said shaft manually, a 115 cross head pivotally mounted on the end of one of said shaft sections, and a trip arm carried by said shaft section for engagement with said rock lever, substantially in the manner and for the purpose set forth.

5. In signaling means of the character 120 designated, the combination of a pivotally supported indicator, a rocker arm pivot-

ally connected therewith, a rock lever pivotally connected with said rocker arm, and fulcrumed on a stationary part, and a reciprocating and rotative shaft formed with a trip arm for engagement with said rock lever, said rotative shaft being formed in two sections flexibly coupled together, and

means for operating said shaft manually, substantially in the manner and for the purpose set forth.

FREDERICK W. HOTTENROTH.
